UNITED STATES PATENT OFFICE.

EMILE MALLALIEU, OF ROSSAL BEACH, ENGLAND.

FLIER OF TEXTILE MACHINES.

Application filed December 31, 1921. Serial No. 526,328.

To all whom it may concern:

Be it known that I, EMILE MALLALIEU, a British subject, residing at Rossal Beach, county of Lancaster, England, have invented certain new and useful Improvements in the Fliers of Textile Machines, of which the following is a specification.

This invention relates to the fliers for the spindles of fly frames used in the preparing of textile fibres for spinning known as slubbing, intermediate, roving and jack frames.

These fliers are constructed with a presser for laying the slub or rove upon the bobbin and as at present constructed the presser body is in the form of a solid rod of circular cross section pivoted upon the side of the hollow leg of the flier but standing away from it.

According to the present invention the flier presser is stamped from sheet metal and the body pressed concave to encircle one leg of the flier and cover the slit therein, the flier is forged with solid legs, one being slotted or grooved to form a passage for the slub or rove.

The invention will be fully described with reference to the accompanying drawings.

Fig. 1. is a front elevation of flier and presser.

Fig. 2. is a sectional elevation of flier with presser removed.

Fig. 3. is an end elevation of flier leg and presser.

Fig. 4. is a plan of flier partly in section at 4—4 Fig. 1.

Fig. 5. is a sectional plan at 5—5 Fig. 2.

Fig. 6. is a sectional plan at 6—6 Fig. 1.

Fig. 7. is a section at 7—7 Fig. 1.

Fig. 8. is an extended blank of presser.

Fig. 9. is a front elevation of presser removed from flier.

Fig. 10. is a sectional plan at 10—10 Fig. 9.

Fig. 11. is a section of modification of presser and hollow leg.

The flier is of the ordinary shape with a hollow or slotted leg A having a yarn passage a through it and a solid leg B.

The presser D is stamped from a flat blank of sheet metal Fig. 8 with two lateral extending members d d' to form clips by which to secure it to the flier leg A and a downwardly extending member to form the arm or paddle E. The body of the presser is pressed by a suitable die to a concave form to correspond with the contour of the flier leg A and is preferably weighted and bent

outwards along one edge at d³ to cause it to swivel around the flier leg when the flier is revolving and maintain the paddle E in contact with and exert the desired amount of pressure upon the surface of the slub or rove as it is wound upon its bobbin, or it may be stamped deeper to add weight as shown in Fig. 11.

The presser arm e is bent to bring the paddle E to the desired position approximately at right angles to the flier leg and the paddle is pierced with an eye to receive and guide the rove on to the bobbin.

The lateral members d and d' are bent round to embrace the flier leg the top one being formed with a groove d⁴ to correspond with a recess or socket a⁴ drilled in the flier leg into which a small ball is placed to prevent a relative movement longitudinally between the flier leg and the presser body.

The flier may be forged with two solid legs and the leg A slotted from end to end to form the yarn passage a therethrough. The slot a may be cut with a milling cutter and the upper portion from e' to f' may be drilled and the slot sawn through with a fine saw. Part of the leg A of the flier may be machined away at a³ and the lip pressed over to close the edge of slot to a fine gauge and leave a very narrow entrance for the rove.

The concave body D of the presser is so attached to the hollow leg A of the flier that when in position for piecing, the edge of the presser body is just clear of the slit in the flier leg see Fig. 3, but when working it covers the slit all the time, thus preventing the air from withdrawing the rove from the passage and also keeping the slit clean and preventing fly or foreign matter from gathering therein, to the detriment of the rove or slub passing down the flier leg.

It is considered that a considerable reduction in vibration will ensue from this construction, and the rove or slub will be kept cleaner from fly and lumps.

What I claim as my invention and desire to protect by Letters Patent is:

1. A flier for textile preparing machines forged with two solid legs and comprising, when finished, a solid leg, a second solid leg with a longitudinal slit machined therein throughout its length to receive the rove and a presser stamped from sheet metal of concave shape and so disposed thereon as to cover and close the slit when in operation.

2. A flier for textile preparing machines comprising in its construction a solid leg, a hollow leg with a yarn passage machined therein throughout its length, a presser 5 stamped from sheet metal, the body part being concave to embrace the hollow leg and cover the slit therein, when in operation, and provided with annular clips to encircle the flier leg and secure the presser thereto, a ball 10 placed in a recess in the flier leg and a groove

in the annular clip on the presser body to engage therewith.

In testimony whereof I have hereunto set my hand in presence of two subscribing witnesses.

EMILE MALLALIEU.
